UNITED STATES PATENT OFFICE.

WILLIAM G. BLAUVELT, OF NEW YORK, N. Y., ASSIGNOR TO AMERICAN TELEPHONE AND TELEGRAPH COMPANY, A CORPORATION OF NEW YORK.

SEMIMECHANICAL TELEPHONE SYSTEM.

1,359,482.

Specification of Letters Patent. Patented Nov. 23, 1920.

Application filed April 11, 1917. Serial No. 161,278.

To all whom it may concern:

Be it known that I, WILLIAM G. BLAUVELT, residing at New York, in the county of New York and State of New York, have 5 invented certain Improvements in Semi-mechanical Telephone Systems, of which the following is a specification.

This invention relates to semi-automatic telephone systems and more particularly 10 concerns the provisions of means whereby when an operator answers a call by inserting the plug of an idle cord circuit into the jack of the calling subscriber, the operator's talking set and associated apparatus will be 15 automatically connected with that particular cord circuit.

It is one of the objects of this invention to provide means whereby the time necessary to effect this operation shall be reduced to a minimum, and the apparatus utilized therefor shall be simple in construction and efficient in operation. It is proposed to accomplish this and other objects hereinafter appearing by providing a sequence switch of the general type shown in 20 U. S. patent to McBerty, 1,105,811 of August 4, 1914, or patent to Reynolds, *et al.*, 1,127,808 of February 9, 1915, common to all of the cords at an operator's position, 25 said switch functioning upon the insertion of the plug of a cord into an answering jack to connect the operator's set to the cord taken for use. This result is accomplished by providing a relay apparatus individual to the cord and operating to connect thereto the operator's set, the circuit of the relay apparatus being under the joint 30 control of a contact of the sequence switch, and a relay contact, or key individual to the 35 cord taken for use.

The invention will be more fully understood by reference to the accompanying drawing Figures 1 and 2 of which when placed end to end comprise a diagram illustrating as much of the circuit arrangement as is necessary to understand the invention.

A single cord circuit is illustrated but it will be understood that there are a plurality of cords at each operator's position, each 50 cord having individual thereto a sequence switch 100 which controls the switching of an idle sending apparatus into connection with a cord taken for use, as well as the

performance of other functions having no part in the present invention and which 55 will not therefore be described. A listening sequence switch 200 is also provided which is common to the operator's position and serves to control the connection and disconnection of the operator's set to a cord 60 taken for use.

Each of these sequence switches is provided with a plurality of contacts which are shown at different points upon Fig. 1 of the drawing in order to simplify the diagram, but in practice the contacts are arranged in a set as shown in the patents above cited. The contacts controlled by sequence switch 100 are designated by numbers whose hundreds digit is 1 while those 70 controlled by sequence switch 200 are designated by numbers whose hundreds digit is 2. Switch 100 has eighteen positions while 200 has but nine positions.

With this brief description in mind the 75 invention may be fully understood from a description of the operation.

Use of connecting circuit when listening sequence switch is in position 1.

Upon the operator inserting the plug P of an idle cord into the jack of a calling subscriber relay 20 is energized and closes its front contacts 21 and 22. Front contact 21 closes a circuit for the listening sequence 85 switch 200 from battery, motor magnet of sequence switch 200, sequence switch contact 201 to common terminal 23 from which branches extend to each of the cords, the circuit in this instance extending from terminal 90 23 over sequence contact 101 in position 1, and over contact 21 of the cord circuit taken for use to back contact 24 of relay 25 and sequence switch contact 202 to ground. This drives sequence switch 200 out of position 1. 95 As it reaches position 2 sequence switch contact 201 opens but under the control of spring 204, closed in all positions except 1 and 7, the sequence switch 200 continues to rotate to position 7, the listening in position, where it 100 stops. As it passes through position 2 the listening relays 25 and 26 are energized over a circuit from battery, relays 26 and 25, lower sequence switch contact 103, contact 22 of relay 20, common terminal 27, lower sequence 105 switch contact 203 to ground. It will be un-

derstood that similar circuits branch from terminal 27 to the listening relays of all the cords of the position. Upon the energization of relay 25 a locking circuit is provided 5 from battery, relays 25 and 26, front contact 24 of relay 25, contact 202 to ground. Simultaneously with the energization of relays 25 and 26 a circuit is established for the distinct sequence switch 100 over upper contact 102, front contact 22 of relay 21, contact 203 now in position 2 to ground, thereby driving 100 into position 2, in which position a sender is associated with the cord as follows: As sequence switch 100 passes 15 into position 2, a circuit is closed from ground, back contact of armature 34 of relay 32, upper contact 107, contact 301 of the cord finder sequence switch 300 and through the winding of the motor magnet of said 20 switch to battery, driving 300 into position 2. A circuit is now closed over the back contact of test relay 40 and upper contact 302 through the winding of the motor magnet 41 of the cord finder switch, which now 25 rotates its wipers 42, 43, 44 and 45 over the contacts of the various cord circuits until wiper 43 rests on contact 47 of the cord which has just been inserted in an answering jack as above described, when a circuit is 30 closed over back contact of armature 34 of relay 32, upper contact 108, contact 47, wiper 43, upper contact 303 and winding of test relay 40 to battery. Test relay 40 now pulls up, opening the circuit of motor magnet 35 41 so that the finder comes to rest, and closing at its front contact a circuit over contact 304 for the motor magnet of sequence switch 300, thereby driving said switch into position 5. In this position a 40 new circuit is established for test relay 40 from ground, over back contact of armature 34, contact 113, contact 46, wiper 42, contact 401 of sender sequence switch 400 winding of relay 50, lower contact 303, 45 winding of test relay 40 to battery. Relay 40 is maintained, energized over this circuit and relay 50 is now energized, closing at the front contact of its armature 51, a circuit over upper contact 402 for the motor magnet 50 41 of sender sequence switch 400, whereby said switch is driven to position 2. The operator now sets up the call upon a key board (not shown) and in so doing closes a contact 53 whereby a circuit for sequence 55 switch 400 is closed over contact 403 driving sequence switch 400 into position 3. Contact 404 is now closed so that the sender, indicated schematically at 54 is connected to the cord circuit over wipers 44 and 45 and contacts 60 114 and 115 of sequence switch 100. As soon as relays 25 and 26 were operated the operator's set was connected to the cord circuit over extension 39 so that the ring back keys 55 and coin control key 56 could be used, as 65 well as the master restoring key 57 and the

master listening out key 58, the purpose of the last two keys being more fully described later.

Use of master restoring key when 100 is 70 not in position 2.

If with sequence switch 100 in a position later than 2 and sequence switch 200 in position 7—the listening in position—the operator desires to listen out, she depresses the 75 master listening out key 58 and drives the listening sequence switch 200 from position 7 into position 1 by a circuit over contact 201, key 58, upper sequence switch contact 203 to ground. In passing through positions 8 and 9 contact 202 opens and unlocks the listening relays 25 and 26. If with switch 100 in position 2, the key 58 is depressed another action takes place which will be described later. 85

Plugging in when 200 is in position 7.

If an operator is listening in on one cord and plugs in with another, her set is cut off of the first cord and onto the second as 90 follows:—When she plugs in with the second cord the relay 20 of that cord operates and drives listening sequence switch 200 out of position 7 by a circuit from ground over upper contact 202 to common terminal 95 28 from which branches extend to the various cord circuits. From 28 the circuit extends over the back contact 24 of listening relay 25 of the cord just plugged in (relay 25 of this cord will be deenergized), front 100 contact 21 of relay 20 of the cord just plugged in, upper contact 101 of sequence switch 100 associated with said cord to common terminal 23, from whence it proceeds over contact 201 (now closed in position 7 105 of sequence switch 200) to motor magnet of said sequence switch 200 and battery.

Switch 200 is now driven to position 1 under control of spring 204, and in position 1 the same circuit is again closed at contact 110 201 and drives 200 into listening position 7, in which the listening relays of the cord last plugged in are locked up. As switch 200 passed through positions 8 and 9 on its way to position 1 the locking circuit of listening 115 relays 25 and 26 of the first cord was opened at contact 202, causing said relays to restore to normal, so that the operator has listened out on the first cord and is listening in on the second. Switch 100 of the second cord 120 is driven into position 2 over contact 102 as described under the first heading.

Listening in, 100 in position 3 to 17 inclusive and 200 in position 1.

125

If while the operator is not listening in on any cord, she desires to listen in on a connection at any time during its course, she depresses listening in key 59 of the desired cord. This causes listening sequence switch 130

200 to be driven out of position 1 by a circuit from ground over contact 202, back contact 24 of listening relay 25, contact 29 of key 59, contact 201, winding of the motor magnet of switch 200 to battery. Upon reaching position 2 listening switch 200 closes a circuit for listening relays 25 and 26 over lower contact 203 and spring 30 of key 59, and these relays lock themselves over contact 24 of relay 25 and contact 202. Listening relay 26 is provided with make before break contacts so that no click is given the subscriber when the operator listens in.

15 *Listening in—100 in positions 3 to 17 inclusive, and 200 in position 7.*

If the operator is listening in on one cord and desires to listen in on a second cord already employed in an established connection, she presses the listening key 59 of the second cord closing a circuit driving listening switch 200 from position 7 to position 1 from ground, contact 202, to common terminal 28, thence over back contact 24 of listening relay 25 of the second cord, spring 29 of key 59, contact 201, winding of 200 to battery. In passing through positions 8 and 9 the listening relays 25 and 26 of the first cord are unlocked. Upon reaching position 1, listening switch 200 is driven to listening position 7 by the same circuit, the listening relays 25 and 26 of the second cord being operated and locked up as described under the first heading.

35 *Listening out—100 in position 2.*

If the operator answers a call by plugging into a jack and desires to listen out from the cord without setting up a connection, it is desirable that the sender which was associated with that cord when she listened in should be disconnected in order that the sender may not be kept idle by being left attached to the connection. If, then, with 45 district switch 100 of the first cord in position 2, and listening switch 200 in position 7, the operator plugs in with a second cord, listening switch 200 will be driven through positions 8 and 9 to position 1, unlocking the listening relays of the first cord, and then driven on to position 7 again. When 200 reaches position 1 on its way to 7, the district switch 100 of the first cord will be driven to position 18 by the following 55 circuits:

From ground, upper contact 202, terminal 28, back contact 24 of relay 25 of the first cord, front contact 21 of relay 20 of the first cord, lower contact 101 of the district 60 switch of the first cord, now in position 2, back contact 31 of listening relay 26 of the first cord, sequence switch contact 104 of the first cord (closed in position 2), winding of relay 32 to battery. Relay 32 is energized 65 and locks up over its contact 33 and upper

sequence switch contact 105 to ground from position 2 to 10 inclusive, and at its contact 34 closes a circuit for sequence switch 100 over lower contact 102, driving sequence switch 100 into position 4 under control of 70 its contact 110. In position 4 relay 37 is energized over a circuit from battery, contact 36 of relay 32, relay 37, contact 107 to ground, thereby closing a circuit for 100 from battery, winding of 100, lower contact 109, contact 38 of relay 37 and contact 108 to ground. Sequence switch 100 is then driven to position 6 through position 5 under control of master contact 110, in which position the circuit over contact 34 of relay 80 32 drives the sequence switch to position 7. In position 7 the circuit controlled by relay 37 drives the sequence switch to position 8 from which it passes to position 14 under joint control of master contact 110 and contact 34 of relay 32. Switch 100 is carried out of position 14 by a circuit closed over the back contact of relay 35 and contact 106, driving the switch into position 17. In this position a circuit is closed for relay 32 over 90 lower contact 105, closing at the front contact 36 of relay 32 a circuit from battery through relay 37 to ground over contact 107. Relay 37 is energized closing a circuit from ground over contact 108, front contact 38 of 95 relay 37 lower contact 109, winding of 100 to battery, driving switch 100 into position 18. As soon as switch 100 passed position 6 the sender was released as follows:

The circuit of the test relay 40 of the cord 100 finder switch was opened by relay 32 on pulling up its armature 34, as well as by the opening of contact 113. Test relay 40 and relay 50 now deenergize, test relay 40 closing at its back contact a circuit over lower contact 302, energizing motor magnet 300 to drive the cord finder sequence switch through position 18 to position 1. The wipers of the finder switch have no normal position but are allowed to remain associated with the contacts of the cord circuit last used. Relay 50 in deenergizing at the back contact of its armature 51 closes a circuit over lower contact 402 to drive the sender sequence switch 400 through position 18 to 105 normal. The sender circuit is now open at contact 404 and as contact 114 and 115 of the sequence switch 100 were opened as that switch passed out of position 6, the sender is disconnected from the cord even though 110 wipers 44 and 45 still rest on contacts 48 and 49.

If instead of plugging in with another cord, the operator, with 100 in position 2 and 200 in position 7 presses the master listening out key 58 a similar effect will be produced as a circuit will be closed for 200 over contact 201 and the spring of 58 to ground over upper contact 203, driving 200 into position 1, unlocking relays 25 and 26, 130

and closing a circuit from ground over contact 202, back contact 24 of relay 25, front contact 21 of relay 20, lower contact 101 in position 2 of switch 100, back contact 31 of relay 26, contact 104 and relay 32 to battery, whereby relay 32 locks up and closes a circuit to drive switch 100 into position 18 as just described.

Listening in, 100 being in position 18.

When the operator wishes to return to a connection such as just described, she depresses the listening key 59 of that cord, sequence switch 100 being in position 18. A circuit for sequence switch 200 is now closed from ground, contact 202, back contact 24 of relay 25, spring 29 of key 59, contact 201, motor magnet 200 to battery, driving 200 to position 7. As it passes through position 2 a circuit is closed for listening relays 25 and 26 over contact 30 of key 59, and lower contact 203 to ground, said relays locking up over front contact 24 of relay 25 and contact 202. A circuit is also closed in position 2 of sequence switch 200 over contact 203, contact 30 of key 59, upper contact 103, winding of motor magnet of switch 100, driving switch 100 from position 18 to position 1, where it is carried into position 2 by a circuit either from ground over lower contact 203, (if sequence switch 200 is still in position 2) thence over front contact 22 of relay 20, upper contact 102, winding of motor magnet of switch 100 to battery, or, if sequence switch 200 has passed beyond position 2, from ground, contact 202, front contact 24 of listening relay 25, lower contact 103, upper contact 102, to the motor magnet of sequence switch 100 and battery. In position 2 of sequence switch 100 a sender is associated with the cord in a manner already described and when sequence switch 200 reaches position 7 the listening relays are locked up in the manner already described.

Use of master restoring key.

At any time when listening in, the district sequence switch 100 being somewhere between positions 2 to 6 inclusive, the operator may control the relay 32, by means of master restoring key 57. When this key is depressed current flows from ground contact of key 57, front contact 31 of listening relay 26, contact 104, relay 32 to battery, said relay pulling up and locking over its contact 33 and sequence switch contact 105. The district sequence switch will then be rotated to position 18 as already described under the heading "Listening out—100 in position 2."

As this result is effected without disturbing listening sequence switch 200 which is now in listening position 7, relay 25 will still be energized and a circuit will be closed from ground over contact 202, front contact

24 of relay 25, upper contact 103 closed in position 18, motor magnet of sequence switch 100 to battery, driving sequence switch 100 into position 1. The sender was disconnected after passing position 6 and 70 associated apparatus restored. In position 1 of 100, 200 still being in listening position 7, a circuit is closed from ground over contact 202, front contact 24 of relay 25, lower contact 103, upper contact 102, motor 75 magnet 100 to battery, driving 100 into position 2, where a new sender is associated with the cord. Thus the old connection has been restored and the apparatus is ready to set up a new connection. 80

The master restoring key is ineffective after the district sequence switch has passed position 6.

Withdrawing plug while listening in.

If, while the operator's set is connected to a cord, listening switch 200 being in position 7, the operator withdraws the plug from the jack, relay 20 is deenergized, but no circuit changes take place, since ground 90 is cut off from contact 21 of relay 20, over contact 202, by reason of the fact that listening relay 25 is energized and its contact 24 does not rest on the back contact leading to armature 21 of relay 20. This permits pulling 95 the plug and re-inserting it without disturbing the connection.

Withdrawing plug while listening out.

If, while listening out, with listening 100 switch 200 in position 1 and the district switch 100 in positions 2 to 6 inclusive, the operator pulls down a cord, the cord is returned to normal, a circuit being closed from ground over contact 202, back contact 105 of armature 24 of relay 25, back contact 21 of relay 20, (now deenergized), back contact 31 of relay 26, contact 104, relay 32 to battery, energizing relay 32, which locks up, and returns switch 100 to position 18 as 110 described under heading "Listening out, 100 being in position 2".

If, however, when the operator pulls down, sequence switch 100 is in a position past position 7, a circuit is closed from 115 ground, contact 202, back contact 24 of relay 25, back contact 21 of relay 20, upper contact 109, motor magnet 100 to battery, driving 100 to position 14, from which position it is carried to position 17 by the line 120 relay 35 and by contact 110, and to position 18 by relay 37 as already described. In position 18, the original circuit over upper contact 109 is closed driving 100 into position 1. 125

Withdrawing plug while listening in on another cord.

If, while the operator is listening in on one cord, she pulls down a second cord, the 130

second cord will be returned to normal as described under previous heading, because since the listening relay 25 of the second cord is deenergized, its armature 24 is on 5 the back contact so that a ground connection to contact 21 of relay 20 exists.

It will be seen from the foregoing that a simple yet efficient means for automatically controlling the connection and disconnection 10 of the operator's set to a cord circuit is provided, and while the invention is shown embodied in a certain form, it will be understood that the embodiment may be widely varied without departing from the scope of 15 the invention as defined in the following claims.

What I claim is:

1. In a telephone system, a plurality of cord circuits, an operator's set, controlling 20 means common to all of the cord circuits, other controlling means individual to each cord circuit, and means under the joint control of said common controlling means and the controlling means individual to a cord 25 circuit for connecting said operator's set to such cord circuit.

2. In a telephone system, a plurality of cord circuits, an operator's set, controlling means common to all of the cord circuits, 30 switching means individual to a cord for connecting the operator's set thereto, controlling means also individual to each cord, and a circuit for said switching means, closed by the joint action of the common 35 controlling means and the controlling means individual to each cord.

3. In a telephone system, a plurality of cord circuits, answering jacks, an operator's set, a listening relay for each cord circuit to 40 connect the operator's set thereto, a controlling relay individual to each cord energized upon plugging the cord into an answering jack, a controlling means common to all of said cords and having a listening 45 in position and a listening out position, said common controlling means assuming its listening in position when said individual controlling relay is energized, and a circuit for said listening relay closed when the individual controlling relay is energized and said common controlling means is in listening 50 in position.

4. In a telephone system, a plurality of cord circuits, an operator's set, a listening 55 relay for each cord circuit to connect the operator's set thereto, a controlling key individual to each cord, a controlling means common to all of said cords and having a listening in position and a listening out 60 position, said common controlling means assuming its listening in position when said controlling key is operated, and a circuit for said listening relay closed when said controlling key is operated and said common 65 controlling means is in listening in position.

5. In a telephone system, a plurality of telephone circuits, a relay individual to each telephone circuit energized when the circuit is taken for use, an extension circuit over which any of said telephone circuits may be 70 extended, connecting means for associating said extension circuit with a telephone circuit, and a common switching means, said connecting means operating under the joint control of said common switching means and 75 a relay individual to a telephone circuit, to connect such telephone circuit to said extension.

6. In a telephone system, a plurality of cord circuits, answering jacks, an operator's 80 set, a controlling means common to all of the cords and having a listening in position and a listening out position, means responsive to the plugging of a cord into an answering jack to cause said controlling 85 means to assume its listening in position, means operative when the controlling means is in listening in position to connect the operator's set to the cord circuit plugged in, and means controlled by the operator to 90 cause the controlling means to assume its listening out position and thereby disconnect the operator's set.

7. In a telephone system, a plurality of cord circuits, answering jacks, an operator's 95 set, a controlling means common to all of the cords having a listening in position and a listening out position, means responsive to the plugging of a cord into an answering jack to cause said controlling means to assume its listening in position, means operative 100 when the controlling means is in listening in position to connect the operator's set to the cord circuit plugged in, and means responsive to the plugging of a second cord 105 into a jack when the operator's set is connected to the first cord to cause the controlling means to assume its listening out position, thereby disconnecting the operator's set from the first cord, and thereafter 110 to again assume its listening in position thereby connecting the operator's set to the second cord.

8. In a telephone system, a plurality of cord circuits, an operator's set, a controlling means common to all of the cords having a listening in position and a listening out position, means operative at will to cause 115 said controlling means to assume its listening in position and thereby control the connection of the operator's set to a particular cord, and means operative at will when the operator's set is connected to one cord to translate said controlling means from its listening in position to its listening out position and then back again to its listening in position, thereby controlling disconnection of the operator's set from said cord and its connection to a second cord. 120

9. In a telephone system, a plurality of 125

cord circuits, an operator's set, a sender, a sequence switch individual to each cord circuit, a listening sequence switch common to all of the cord circuits and having a listening in position and a listening out position, means operative when said listening sequence switch is in listening in position to connect the operator's set with a cord, means operative when said listening sequence switch has moved out of its listening out position, to cause the sequence switch individual to a cord to assume an off-normal position, means operative when the individual sequence switch is in such off-normal position to cause the sender to be associated with the cord circuit, and means under the control of the operator operating to cause said listening sequence switch to assume its listening out position, thereby disconnecting the operator's set.

10. In a telephone system, a plurality of cord circuits, an operator's set, a sender, a sequence switch individual to each cord circuit, a listening sequence switch common to all of the cord circuits and having a listening in position and a listening out position, means operative when said listening sequence switch is in listening in position to connect the operator's set with a cord, means operative when said listening sequence switch has moved out of its listening out position, to cause the sequence switch individual to a cord to assume an off-normal position, means operative when the individual sequence switch is in such off-normal position to cause the sender to be associated with the cord circuit, said individual sequence switch having other off-normal positions, and means under the control of the operator operating to cause said listening sequence switch to assume its listening out position and also causing the sender to be released if the individual sequence switch is in its first off-normal position, but operating to disconnect the operator's set without releasing the sender if the individual sequence switch is in another off-normal position.

11. In a telephone system, a plurality of cord circuits, answering jacks, an operator's set, a controlling means common to all of the cords having a listening in position and a listening out position, means responsive to the plugging of a cord into an answering jack to cause said controlling means to assume its listening in position, means operative when the controlling means is in listening in position to connect the operator's set to the cord circuit plugged in, and means controlled by the operator to cause the controlling means to assume its listening out position and thereby disconnect the operator's set, and means operative when the plug is withdrawn while the operator's set is disconnected to restore the cord circuit to

normal, but ineffective if the plug is withdrawn while the operator's set is connected.

12. In a telephone system, a plurality of cord circuits, an operator's ringback and coin control key common to said cord circuits, controlling means common to all of the cord circuits, other controlling means individual to each cord circuit, and means under the joint control of said common controlling means and the controlling means individual to a cord circuit, for connecting said operator's keys to an individual cord circuit.

13. In a telephone system, a plurality of cord circuits, an operator's set, a sender, a sequence switch individual to each cord circuit, a listening sequence switch common to all of the cord circuits and having a listening in position and a listening out position, means operative when said listening sequence switch is in listening in position to connect the operator's set with a cord, means operative when said listening sequence switch has moved out of its listening out position, to cause the sequence switch individual to a cord to assume an off-normal position, means operative when the individual sequence switch is in such off-normal position to cause the sender to be associated with the cord circuit, said individual sequence switch having other off-normal positions, means under the control of the operator operating to cause said listening sequence switch to assume its listening out position and also causing the sender to be released if the individual sequence switch is in its first off-normal position, but operating to disconnect the operator's set without releasing the sender if the individual sequence switch is in another off-normal position, and means under the control of the operator after the sender has been thus released to cause the individual sequence switch to assume its first off-normal position whereby a sender is again associated with the cord circuit.

14. In a telephone system, a plurality of cord circuits, an operator's set common to said cord circuits, controlling means common to the cord circuits, other controlling means individual to each cord circuit, means under the joint control of said controlling means to connect the operator's set to a cord circuit and associate a sender therewith, and means whereby an operator while listening in may restore a set up connection and prepare the apparatus associated with the cord circuit for a new connection.

In testimony whereof I have signed my name to this specification in the presence of two subscribing witnesses this third day of April, 1917.

WILLIAM G. BLAUVELT.
